UNITED STATES PATENT OFFICE.

PATTERSON D. MERRILL, OF CHICAGO, ILLINOIS.

SHORTENING MIXER.

Application filed September 8, 1924. Serial No. 736,415.

The present improvements are in devices for mixing lard, butter, or other forms of so-called "shortening" into flour, in the making of cake, pastry and various other articles of food.

It is desirable to avoid the use of the operator's hands in mixing the flour and shortening together. For one reason the most satisfactory mix can not thereby be obtained, and the mixing by hand is unsanitary and is also unpleasant to the operator. It is not new to provide an instrument for mixing the mentioned ingredients, as witness the patent to Palmer No. 1,374,086 of April 5, 1921 and that to Geiger, No. 1,417,985 of May 30, 1922.

I have discovered through my experimentation that the most satisfactory mix is obtained when the shortening and the coagulated lumps in the mass are cut cleanly and sharply as distinguished from mashing, and also that the cutting device be such that the possibility of adherence thereto by the shortening is reduced to the minimum. I have also found it desirable to have the cutters substantially close together and substantially numerous in order not only to expedite the mixing operation but to insure the desired results, which is to divide the shortening into a multitude of very small particles, and make a crumbly mix as distinguished from a pasty one, or one partly crumbly and partly pasty, or one in which substantial masses of the shortening occur.

The principal objects of the present improvements are to provide a device through the use of which the foregoing results and advantages may be obtained, and to provide a mixer of simple, strong and durable construction, easy to clean after use, and easy, rapid and usually effective in operation.

In the accompanying drawings, which form a part of this specification, Figure 1 is a bottom view of the device; Fig. 2 is a substantially medial sectional view, as on the line 2—2 of Fig. 1; and Fig. 3 is a side view of the body portion.

In my practice the body or frame 10 is a trough-like aluminum casting which may well be from three to four inches in length, and which may well be from two and one-half to three inches in width for ordinary household use. It may well be of larger dimensions where the mixing is done on a larger scale. Means such as the screw 11 are provided for holding the handle 12 firmly upon

the body in a medial position on the back or normally upper part thereof as illustrated.

A plurality of lengths of relatively fine wire 13 are positioned taut across the open bottom of the frame 10, and these wires 13 are preferably in substantially parallel relation to each other and substantially close together, and they form a series of cutters extending substantially from end to end of the frame. In my practice I find that a spacing of about a quarter of an inch to three-eights of an inch between the wires 13 is satisfactory. If the wires be too close to each other the operation will not be as free, for in such case the wires hold the mix objectionably above the wires, while with the proper spacing the instrument readily comes out of the mix and performs its desired function on both the downward and upward stroke. If the wires are spaced fairly widely apart the instrument loses much of its efficiency in rapidly reducing the mass to a crumbly consistency.

In my practice the wire lengths 13 are sections of a continuous wire leading from one end of the device to the other. To accomplish this result in a convenient and satisfactory way, while providing for the ready replacement of the wire lengths if desired, I provide on each side of the body 10 a plurality of outstanding lugs 14, the lugs on one side being staggered with respect to the respective cooperating ones on the other side of the body. The tops of these lugs are rounded as indicated, and each lug is provided with a retaining recess at its top at 15 adapted to hold the wire securely. The arrangement of the lugs and the width given them respectively insures that the wires 13 shall lie straight across and have the desired spacing from each other and be maintained in their desired relative positions throughout all conditions of use.

In order to secure the wire in its desired position I place the body 10 in a vise with its open end upward and then draw the sides toward each other slightly placing the body under expansive spring tension. I then secure one end of the wire as at 16, Fig. 3, to the body, as by passing it through a small hole bored therein, and then simply draw the wire back and forth across the open bottom and around the lugs respectively until the wire lengths extend from one end of the device to the other, and then similarly fasten the other end of the wire.

The wire can be drawn by hand fairly tightly, but not as tightly as is desirable, but upon taking the body out of the vise the side walls spring apart and the wires ⁵ are drawn taut.

The wire which I employ for this purpose is what is known as piano wire, which has a notably great tensile strength, and its diameter is preferably about twenty-thousandths to twenty-two-thousandths of an inch. The fineness of the wire is an important feature. Being so fine, and being drawn so taut, it cuts the shortening and the coagulated masses cleanly and easily, ¹⁰ and avoids the objectionable mashing which results in a pasty sort of mix.

The frame 10 is preferably in the form shown, namely that of an inverted trough open at its ends, the sides of which taper ²⁰ toward the top sufficiently on the inside to free the material within it and avoid an accumulation of the material within the body. The sides are nicely polished and the material comes away readily during the mixing operation. It is desirable to maintain the mix cool during the operation, and its contact with the metallic walls of the body help in that direction. Constructed in the manner shown, the body provides a strong ²⁵ spring member having the capacity of holding the wires taut. Furthermore, the body consists of relatively large unbroken surfaces free of openings from which the material would be difficultly removed. The ³⁰ body is unusually strong and the construction as a whole is such as to protect the wire lengths to a notable degree.

The instrument is used by simply moving it up and down in a container for the

mix, turning it about from time to time in the hand to make the cuts at various angles. The device is readily cleaned by putting it under the hot water faucet or by stirring it about in a bowl of hot water.

I contemplate as being included in these ⁴⁵ improvements such variations and departures from what is specifically illustrated and described herein as fall within the scope of the appended claims.

I claim:

1. In a shortening mixer, the combination of a substantially U-shaped body in cross view normally inverted, smooth interiorly and open at its ends, a handle therefor normally extending upward, and a plurality of ⁵⁵ lengths of substantially fine wire spaced apart and spanned from side to side of said body and held taut thereby.

2. A shortening mixer of the character described comprising a normally-inverted trough-shaped body, hand-hold means for operating the device, and a plurality of lengths of substantially fine wire substantially parallel to each other spaced substantially uniformly short distances apart and ⁶⁵ extending from side to side of the body member, held taut by spring tension in the body member, and forming a series of cutters extending substantially from end to end of the body member.

3. In a shortening mixer, the combination of a body having a handle and a pair of integral side members adapted to be put under expansive spring tension, and a plurality of lengths of fine wire spaced apart ⁷⁵ side by side and held taut between and by said side members.

PATTERSON D. MERRILL.
